UNITED STATES PATENT OFFICE.

DAVID P. MONROE, OF ATTLEBORO, MASSACHUSETTS.

RAIL-JOINT.

SPECIFICATION forming part of Letters Patent No. 729,081, dated May 26, 1903.

Application filed March 20, 1903. Serial No. 143,800. (No model.)

To all whom it may concern:

Be it known that I, DAVID P. MONROE, an alien of Canada, having filed my declaration of intention to become a citizen of the United States, residing at Attleboro, in the county of Bristol and State of Massachusetts, have invented certain new and useful Improvements in Rail-Joints; and I do hereby declare that the following is a full, clear, and exact description of the same, reference being had to the annexed drawings, making a part of this specification, and to the letters of reference marked thereon.

The present invention has for its object to provide a simple, rigid, and effective joint for connecting together the ends of abutting rails, whereby the same will be held and maintained in perfect alinement and effectually prevented from displacement or one rail rising above the other, the joint being equally applicable to all classes of rails, whether the ordinary T-rail or the rails used with the underground-trolley system.

The invention consists in a joint for the coupling together of the abutting ends of railroad-rails constructed substantially as shown in the drawings and hereinafter described and claimed.

Figure 1 of the drawings is a perspective view showing a portion of a railroad-track with the ordinary T-rails and the girder-rails coupled together by my improved joint; Fig. 2, a perspective view, on an enlarged scale, of the two sections of rail-joint which is adapted for attachment to the end of the ordinary T-rail; Fig. 3, a similar view of the two rail-joint sections for the attachment to the end of the girder-rail used in the underground-trolley system.

In the accompanying drawings, A represents the ordinary T-rails, and B the girder-rails, both of which are supported upon the usual cross-ties C of a railroad-track and held thereon by spikes a or other means found most preferable. The joint with which the T-rails and girder-rails are connected together consists, in part, of the two chair-sections D E, having depending blocks F, which abut against each other when the two chair-sections are brought together, each chair-section having an upwardly-extending fish-plate G, between which the rails are held, and se-

cured thereto by suitable bolts b and nuts c, the bolts extending through said plates and rails in the usual manner.

55

The construction shown in Fig. 3 of the drawings is especially adapted for connecting to the end of a girder-rail, as indicated at B in Fig. 1 of the drawings, and in this particular the fish-plates are of greater width than the fish-plates used for the ordinary T-rail.

The construction shown in Fig. 3 of the drawings comprises two box-sections H I, so that when brought together will form a complete box, with which the blocks F engage in coupling the abutting ends of the rails together. The box-sections H I have projecting flanges d at their base, so as to enable the head of the spike a to overlap the same in connecting said box-sections to the cross-ties. The box-sections H I are cast or otherwise provided with suitable fish-plates J to adapt them for attachment to the sides of a girder-rail through the medium of bolts e and nuts f. The fish-plates J have longitudinal ribs g upon their inner sides to better clamp the plates against the sides of the rail through the medium of the bolts and nuts or other fastenings used. When the fish-plates G J are connected to the rails A B, respectively, and the blocks F engaged with the box when the two sections H I are together, and the bolt h, which passes through the sections and blocks, connects them together and tightly draws the box-sections against the blocks by means of the nuts i, a perfect and practical joint is provided that can be adapted to any size rail of whatever construction.

I do not wish to be understood as limiting my invention to any special form or construction of rail or any special form or construction of fish-plate, as the fish-plates may be variously modified or changed without in any manner departing from my invention.

95

Having now fully described my invention, what I claim as new, and desire to secure by Letters Patent, is—

1. A joint for coupling together the two abutting ends of the ordinary T-rail and girder-rail, comprising suitable fish-plates adapted for attachment to the sides of the T-rail and suitable fish-plates adapted for attachment to the sides of the girder-rail, and means for

100

coupling the two pairs of fish-plates together, substantially as and for the purpose set forth.

2. In a rail-joint, a chair for the rails formed in sections having upwardly-extending fish-plates and depending blocks, in combination with a box formed in sections and having suitable fish-plates, the blocks adapted to engage the sectional box, and means for

securing the blocks therein, substantially as and for the purpose described.

In testimony whereof I affix my signature in presence of two witnesses.

DAVID P. MONROE.
